E. H. GOVE

PENDULUM OR SWINGING FLUSH VALVE FOR WATER CLOSETS

Filed Sept. 13, 1926

UNITED STATES PATENT OFFICE.

EDWARD H. GOVE, OF BIDDEFORD, MAINE; EVERARD J. GOVE EXECUTOR OF SAID
EDWARD H. GOVE, DECEASED.

PENDULUM OR SWINGING FLUSH VALVE FOR WATER-CLOSETS.

Application filed September 13, 1926. Serial No. 135,135.

My invention relates to a flush-valve operating mechanism for the flush-tank for water-closets.

More specifically, my object concerns certain improvements in the flush-valve mechanism for which a patent was granted me May 25, 1926 Numbered 1,586,193, and in which a one-piece valve spindle making pivotal connection with the lifting lever 10 was employed.

In my present invention I utilize the one-piece-spindle feature, but adopt other means for the engagement of these elements,—the spindle and lever, in the operation of lifting 15 the valve.

As in my former invention, my present one eliminates the spindle joints and the guide quite generally employed in the conventional type valve-lifting mechanism,—this guide 20 element comprising a fixed arm extending from the overflow pipe and engaging the valve-spindle, restricting it in its lateral movement to very close limits.

Another object, in line with the elimination 25 of parts, is to so construct and allocate the mechanism that certain elements already in or on the tank may be utilized to control and limit the upward movement of the valve.

With these and other objects in view the invention consists in the novel features hereinafter shown and described, and in the drawings illustrative of the preferred embodiment of my invention and in which like 35 characters of reference indicate similar parts throughout all the different views,—

Fig. 1 is a fragmentary sectional elevation of a flush-tank showing my flush-valve installed therein;

Fig. 2 is an elevation of the valve-and-spindle unit;

Fig. 3 shows the emergency stop collar functioning as means to limit the abnormal upward movement of the valve;

Fig. 4 illustrates an alternate method of stopping the valve at its normal upward position, and

Fig. 5 is an alternate design of the water-way spindle.

Referring to Fig. 1, 1 represents any ordinary flush-tank, 2 the cover therefor, 3 a spud member provided with a valve-seat 4, and 5 is the flush-valve. 6 is the usual pipe nipple extension from the spud member and

7 is the pipe which conducts the outgoing water from the tank to the water-closet. The overflow pipe is seen at 8.

Any suitable hand-operated mechanism may be employed to raise the valve from its seat,—as for instance, the conventional type shown, having a handle 9 fixed to a shaft which, when actuated causes the arm 10 to abut on one end of the lifting-lever 11,—the latter being pivotally hung in a proper supporting bracket at 11'. A vertically disposed hole 12 is made in the lifting-lever at the spindle contacting end thereof.

The foregoing parts are common to most flush-tanks.

In Fig. 2 I illustrate my complete flush-valve unit, comprising in its make-up the valve 5 with its lower portion 5' made in semi-spherical form, the valve-spindle 13 and the water-way-spindle 14. The valve-spindle is fixed in the nut 15 (see Fig. 1.) 75 and is provided with a collar 16 which is adjustably secured on the valve-spindle and operates always above the lifting-lever 11.

It is very important that vertical adjustment of the collar 16 on the valve-spindle 80 13 be possible for the reason that in different types and designs of flush-tanks the distance from the lifting-lever to the valve seat varies, and it is essential that a small intervening space be always maintained between the collar and the upper face of the lifting-lever when the valve is seated,—otherwise the collar would either hold the valve off its seat or prevent its coming firmly thereonto.

I have shown the collar as making a sliding fit over the valve-spindle and secured thereto by the set-screw; it is obvious that a mechanical equivalent for the set-screwed collar would be a nut, screw-threaded on to 95 the valve-spindle.

Subsequent to the raising of the lifting-lever to its extreme "up" position, the valve, being buoyant, will continue to rise until the upper end of the valve-spindle contacts with the tank cover 2,—the position of the collar 16 now being as indicated at 16^b,—with the cover in this instance serving as a stop to limit the normal upward movement of the valve.

As just previously stated, flush-tanks vary in depth, according to the type and design of the builder; so when these valve-and-

spindle units are furnished as equipment for flush-tanks already installed, the spindles are supplied over-length and the upper ends clipped off to fit the tank measurement in each individual case.

In the event that the tank cover 2 be removed for any purpose during the flushing period, I have provided an emergency stop-collar 17, which also is adjustably secured to the valve-spindle 13, below the lifting-lever 11 (see Fig. 3). While the valve-spindle may then rise above the top of the tank, the collar 17 abutting on the underside of the lifting-lever, which is limited as to upward movement by the stop 18, prevents the water-way spindle 14 from completely withdrawing out of the spud water-way 19. Thus the valve is held under limited lateral control at all times.

20 It is one of the distinct features of my present invention to allow the valve a relatively large side-wise play in all directions when off its seat,—in other words, to allow it to freely follow the gyratory movements 25 of the water during the flushing period and restrain it only when these movements become excessive.

In my former patent, hereinbefore referred to, the spindle was restricted to 30 movements allowable with a pivotal connection of the spindle with the lifting lever, but in my present invention I have sought to obtain the greatest possible latitude of 35 action, both vertically and horizontally in all directions, of the valve while lowering to its seat, and I accomplish this object by providing telescopic engagement of the valve-spindle with the lifting-lever and allowing greater liberty of lateral action of 40 the water-way spindle in the spud water-way. In Fig. 5 of my drawings I show a water-way spindle with the lower end constructed somewhat after the same lines as the same element in my former patent,— 45 except that it is greatly constricted, for the reason which I have just explained.

I may elect to construct this element as 50 illustrated in Figs. 1 and 2 in which is shown an offset portion, on one side only of the water-way spindle. The object of this 55 offset is to provide a slight obstruction to the passage of the outgoing water which tends to throw the extreme end of the water-way spindle toward the center of the water-way and prevent its coming into contact with or lodgment on any shoulders or uneven surfaces on the interior of the water-way passage,—a result which might obtain should the spindle be made straight.

60 I am not particularly concerned with the exact mechanical construction or shape of the end of the water-way spindle so long as its size provides a relatively large amount of side play of the spindle within the water-way in all directions, and its end so shaped

as to eliminate the possibility of its hanging up on any obstruction within the spud opening.

In Fig. 4 I illustrate an alternate method of providing a stop to limit the 70 vertical movement of the valve-spindle. In this instance a cross-bar 20 serves as the equivalent of and acts in the same capacity as the tank cover in the first method described. 75

In operation, the lifting-lever raises the spindle and the valve to a position as indicated at 5°, bringing the valve off its seat and releasing the water from the tank. Immediately the user releases the handle 10, 80 the lifting-lever drops back to its original position, but the valve continues to rise until the end of the valve-spindle strikes the cover 2 or the cross-bar 18. After the water lowers in the tank sufficiently to allow the valve to float, the latter may and will gyrate with and follow the swirling of the water discharging from the tank, the one-piece spindle easily sliding downwardly through the orifice in the lifting-lever and the water-way 85 spindle controlling the side-wise movements of the valve to prevent them becoming abnormal. Under these conditions the valve will come easily and accurately to its seat, unhampered by closely fitting guides or 90 movement restricting devices which tend to create friction and cocking of the contacting parts. 95

The construction of parts embodied in the apparatus is of the simplest form, the work 100 of installing in or removing from a flush tank the least and the cost of maintenance very low.

Having thus described my invention, what I claim is:

1. In a device of the character described comprising in combination a valve, a valve seat, a water-way, a valve-lifting lever having a vertically disposed hole near its end, an integral valve-lifting spindle, one end being secured in said valve and the other end making a sliding connection with said valve-lifting lever through the said vertically disposed hole therein, means on said valve-lifting spindle, superjacent said valve-lifting lever, to raise said valve, and means sub-jacent said valve and operable between the walls of said water-way, to permit of a relatively large amount of lateral movement of said valve when off its seat. 110

2. In a device of the character described comprising in combination a valve, a valve seat, a water-way, a valve-lifting lever having a vertically disposed hole in the free end thereof, a one-piece valve-lifting spindle, one end being fixed in said valve and the other end reciprocable in the vertically disposed hole in said lifting lever, means adjustably secured to said valve-lifting spindle, superjacent said valve-lifting lever, 115

whereby said valve may be raised, and a water-way spindle depending from said valve and adapted to permit of a relatively large lateral movement of said valve when off its seat, said movement being restricted only by the engagement of said water-way spindle with the walls of said water-way.

3. In a device of the character described comprising in combination with a valve, a one-piece valve-lifting spindle and a water-way spindle having a relatively large per-

missible movement, laterally, when said valve is off its seat, of a valve-lifting lever having a vertically disposed hole near its free end through which said valve-lifting spindle may reciprocate, and means on said valve-lifting spindle, superjacent said valve-lifting lever, whereby said valve may be raised.

Signed at Biddeford, county of York and State of Maine, this 4th day of August, 1927.

EDWARD H. GOVE.
